(57) **CLAIM**

The ornamental design for a stethoscope chest piece, as shown and described.

DESCRIPTION

FIG. 1 is a perspective view of a stethoscope chest piece showing my new design;

FIG. 2 is a side elevational view thereof, the opposite side view being a mirror image thereto;

FIG. 3 is an end elevational view thereof;

FIG. 4 is an end elevational view thereof, the opposite shown in FIG. 3;

FIG. 5 is a top plan view thereof; and,

FIG. 6 is a bottom plan view thereof.

The surfaces or portions of the article not shown in the drawings or described in the specification from no part of the claimed design.
